COSMETIC CONTAINER

William C. Rainer, Baltimore, Md., assignor to Crown Cork & Seal Company, Inc., Baltimore, Md., a corporation of New York

Application February 1, 1955, Serial No. 485,463

8 Claims. (Cl. 132—79)

The present invention relates to a cosmetic container having a plurality of liners, one of which has a mirror surface.

It is an object of the present invention to provide a cosmetic container with a liner having a mirror surface.

Another object of this invention is to couple such a liner with the inner protective liner of the container.

An additional object is to increase the resistance of the contents of the container against penetration of gases and water vapor and which is, therefore, resistant to atmospheric infiltration.

A further object of the invention is to provide a liner surface which can be readily freed from contents of the container which occur thereon due to creepage.

A still further object of this invention is to provide liners for cosmetic containers which are grease-proof and are also tough and flexible.

Still further objects and the entire scope of applicability of the present invention will become apparent from the detailed description given hereinafter; it should be understood, however, that the detailed description and specific examples, while indicating preferred embodiments of the invention, are given by way of illustration only, since various changes and modifications within the spirit and scope of the invention will become apparent to those skilled in the art from this detailed description.

The present application is a continuation-in-part of my copending application Serial No. 299,142, filed July 16, 1952, now abandoned.

In the drawings, there is shown a preferred embodiment of the invention.

Figure 1 is a cross section showing a container cover having a mirrored liner therein.

Figure 2 is a cross section showing a container having a protective inner liner attached thereto.

Figure 3 is a cross section showing a container with the cover and mirrored liner in place on the container, the mirrored liner being on top of the protective inner liner.

Figure 4 is a perspective view showing the mirrored liner and the cover.

Figure 5 is a cross section showing an alternative form of a container cover having a mirrored liner therein.

Figure 6 is a cross-sectional view similar to Figure 1, but showing a preferred form of the invention, wherein the mirrored liner has a thin coating of a silicone;

Figure 7 is a cross-sectional view similar to Figure 2, but illustrating the use of a silicone coating on the protective inner liner;

Figure 8 is a cross-sectional view similar to Figure 3, but showing the preferred modification wherein a thin film of silicone is employed.

Referring to the drawings, it can be seen that the protective inner liner 2 has a flat peripheral edge portion 4 resting upon the edge 6 of a container 8. Disposed inwardly of this edge portion, the protective inner liner is provided with a depending bead 10, preferably of V- or U-shaped cross section. The outer side of the bead has a surface 12 which extends inwardly and is inclined in-

2

wardly and downwardly. The inner side of the bead has a surface 14 which extends outwardly and is inclined upwardly and outwardly. The surface 12 engages the container wall at the inside of the edge 6. The maximum diameter of the edge portion 4 of the protective inner liner is greater than the diameter of the inside surface 16 of the container wall.

The cover 18 has a downwardly extending flange 20 having internal threads 22 which are adapted to engage the threads 24 on the outer surface of the container.

There is also provided a second plastic liner 26 having a metallized face to form a mirror surface 28. The second liner is embossed to provide an annular shoulder 30 above its planar circumference and adjacent its periphery.

15 The second liner 26 is thus conditioned to nest snugly within the similarly contoured ring-like recess of the plastic inner protective liner 2 of the container, when the closure is screwed into its final sealing position, as shown in Figure 3.

20 Preferably, the mirrored second liner is permanently secured within the cover so that, when the cover is removed, the liner is immediately available as a mirror. The rounded annular shoulder on the mirrored liner, preferably, projects about 0.035" above its planar circumference.

25 The mirror surface can be applied to the plastic liner 26 by metallizing the surface thereof with an infinitesimal deposit of aluminum, silver, or other metal, to form a unitary liner. The liner 26 can be made completely out of plastic or, in the alternative, the liner can be made of a pulpboard cushion faced with a plastic. Sometimes, it is advantageous to employ both a mirrored plastic liner and a separate pulpboard liner which can serve as a backing therefor or otherwise function as a conventional pulpboard liner.

30 The liners 2 and 26 can be made of the same or different plastics and both of them or only liner 26 need be metallized. Film-forming plastics in general can be used to form the plastic liners. Typical examples of such materials are cellulose esters, e. g., cellulose acetate, thermosetting or thermoplastic synthetic resins, e. g., polystyrene, bilaterally oriented copolymers of styrene with acrylic materials, such as acrylonitrile or methyl methacrylate and bilaterally oriented polymerized methyl methacrylate.

35 Cellulosic liners have certain defects which influence their dimensional stability, e. g., due to plasticizer extraction or migration and, hence, render them less than ideal.

40 Certain of the synthetic plastics, while being suitable as liner material, also have defects which render them less than perfect.

45 It has been found that the difficulties encountered with these and other materials can be overcome by using bilaterally oriented polystyrene as the plastic in forming mirrored liner 26 and, preferably, in forming inner protective liner 2. The bilaterally oriented polystyrene has superlative characteristics of age stability, grease-proofness, moisture impermeability, transparency, reflectivity, and rigidity which, together with great toughness, cause it to function as the preferred liner material in the present invention.

50 Polystyrene, which is not bilaterally oriented, is too brittle to be an ideal liner. It has been discovered that this inherent weakness in polystyrene can be overcome without the aid of plasticizer inclusion, which tends to impair its chemical strength, by stretch-orienting the plastic both longitudinally and laterally, so as to increase the original area of said plastic by 900%. Polystyrene, which has been bilaterally oriented in sheet form, manifests, in relation to unoriented stock, a crazing strength increase of approximately 400%, and a tensile strength increase of about 200% in the direction of stretch, as well as induced flexibility and added toughness. Pure

polystyrene sheets, thus modified, have window-like transparency and vibrate with a metallic ring, resembling, paradoxically, metal glass. Liners, fabricated from such bilaterally oriented polystyrene, require no modifying components, as opposed to the previous types of cellulose composition and are therefore, more chemically inert, and better suited to retain indefinitely the aforementioned qualities and, additionally, are more easily fabricated into the previously disclosed shapes or any of the shapes taught in Patent No. 1,995,350, for example, and will not fracture with usage.

Orientation, as applied to plastics, signifies that the molecules have been displaced from a completely haphazard distribution into some more orderly arrangement.

Longitudinal orientation produces longitudinal molecular arrangements by reason of the lengthwise stretching of an extruded sheet of uniform cross section in the temperature range where the material is rubbery.

Lateral orientation develops linear molecular arrangements by reason of the side stretching of an extruded sheet in the temperature range where the material is rubbery.

Bilateral orientation is an expression of the combined lateral and longitudinal stretching of an extruded sheet under controlled temperature conditions. The strength of the extrusion is thereby increased in both directions with a corresponding reduction in strength, in the direction straight through the thickness of the sheet where the stress of external forces is the least. The molecules do not change the angle of their extended contours with respect to the length or width of the sheet but line up into position more nearly parallel to the surface.

Bilaterally oriented polystyrene may be produced, for example, by the Plax method, in which the extruded sheet is initially directed through a series of metal cooling rolls (approximately 160° F.) which supplies the necessary tension to the sheet and then travels through an oven at 255° F., which distributes the temperature uniformly over the entire sheet. The sheet next passes to the stretching oven where its travel is accelerated by the side grippers to a speed of 2½ to 3½ times its delivery to the oven, developing thereby a corresponding longitudinal stretch. Here, it is likewise expanded laterally so that a dual stretch is imparted to the whole. In the stretching oven, the sheet is subjected to a temperature gradient from 240° F. at the entrance to 250° F. in the center area, down to 175° F. at the exit. Finally, the sheet is cooled, trimmed and wound on cylinders.

By reason of the flexibility and ruggedness imparted by means of bilateral orientation to the otherwise brittle polystyrene film, successful stamping and embossing thereof have been accomplished. Even though stamping and embossing are effective at ordinary temperatures, the delicate character of the latter is enhanced at elevated temperatures. Since the applied load is proportional to the operating speed and the temperature of the die and plastic, it is preferred to use a temperature of 200° F. and an embossing pressure of 10,000 pounds. The applied pressure of 10,000 pounds, however, may be subject to change, depending on the speed and the embossing definition desired.

The 200° F. operating temperature is preferred in view of the elastic memory of the polystyrene film. When completely relaxed, the film will remain dimensionally stable at any temperature, unless an external stress be applied. If however, it has been stretched, e. g., through orientation, it tends to resume its relaxed shape and will contract as soon as its temperature is raised to the point where mobility commences, which lies between 210° and 215° F.

Either or both of the liners 2 and 26 can be tinted, e. g., of an eggshell blue or flesh pink color, to add to the saleability of the cosmetic preparation, although, this is not essential. If desired, the protective inner liner 2 can also be metallized.

By employing a dual liner system in the closure-container combine, the sealing character thereof is proportionately enhanced and the delicate surface 28 of the closure liner mirror is retained unsullied. This is accomplished by having the rounded annular shoulder 30 of liner 26 nest snugly within the ringlike recess 10 of the protective liner 2 in the manner previously described. Thus, there is a close and intimate contact between the liners 2 and 26 substantially throughout their entire surface areas.

In addition to its other functions, the ring-like recess 10 of the protective liner 2 effects extended surface contact to engage the inner circumferential wall of the container. As it also receives the annular shoulder 30 of the liner 26 totally within its confines, it serves to complement the strength of the inner seal by virtue of the rigidified contours of the liner couple joining forces and exerting a double pressure influence downwardly and laterally against the contacting surface areas of the container wall. The intimacy of contact between the specially constructed liners 2 and 26 also functions as an additional sealing aid to insure maximum protection against atmospheric infiltration in order to preserve the delicate texture of the contents of the container from oxidative influences or the influence of moisture.

The container itself can be made of any conventional material, such as metal, glass, ceramics, cellulose esters, thermosetting or thermoplastic resins. The cover, likewise, can be made of any one or a combination of these conventional materials. As shown in Figure 5, it is frequently desirable to insert the mirror liner 26 in a vertically sided metal cover shell 32 prior to assembly of the inner metal thread 34. Both the liner and metal thread are then locked into position with the aid of inward and upward curling of the raw edge of the shell extremity as at 36.

Capillarity has frequently created problems in the packaging of cosmetic creams, emulsions, etc., and there have been various methods proposed to eliminate or reduce this effect. One suggestion has been to provide a cap liner and an inner disc within the container which are spaced apart sufficiently to break the capillary action.

While the primary purpose of the present invention is to form a composite seal including a mirror surface and to effect maximum protection of the container contents against the ravages of atmospheric oxidation, still, the present container-closure system is also effective to a considerable extent in reducing capillarity. The rigidity of the embossed inner liner 2 and embossed cap liner 26 which, upon engagement with each other set up radial stresses outward from the rim of annular contact, tends thereby to confine product creepage to the circumferential areas. However, if some creepage should develop over the inner surfaces, easy removal of the same can be accomplished by mere wiping of the surfaces of the inner liner and the cap liner carry a minute film of silicone which is a preferred embodiment of the present invention. This form of invention is illustrated in Figures 6 to 8 which disclose (Figure 6) the use of a minute film of silicone 40 as a coating for the liner 26 and (Figure 7) a similar minute film of silicone 42 as a coating for the liner 2. Figure 8 shows the minute film of silicone 44 which is a merger of coatings 40 and 42 and which results when the liner 26 is placed in position on top of the liner 2. The silicone, preferably, is employed as a lubricant in cutting and embossing the inner liner and the cap liner. The very small amount of silicone thus formed on the surfaces of the liners is effective for the intended purpose. The silicone serves the additional purpose of a destaticizer and also aids in preventing of sticking of the liners to the container or to each other. Various silicones can be used, including the alkyl or alkyl-aryl, e. g., the polydimethyl siloxanes and various mixed polymethylphenyl siloxanes.

What is claimed is:

1. In combination, a container having an opening therein bounded by a wall having an edge, a first plastic liner disc extending across said opening and having a peripheral portion thereof engaging said edge of the container, an annular surface on said disc disposed inwardly of said edge portion thereof and engaging said wall within said edge and extending downwardly within the opening and inclined away from the wall to form a recess, a second plastic liner disc having a thin metal coating thereon to form a mirror surface, said second disc having an annular shoulder thereon contoured to fit said recess, said second disc removably resting snugly on top of said first plastic disc with said shoulder fitted in said recess, a cover for said opening of greater diameter than the opening and extending across said edge, said second disc being permanently secured within said cover and means to secure the cover to the container.

2. The combination of claim 1, wherein said inclined surface is formed by the outer surface of a depending circular bead formed in the first disc.

3. The combination of claim 1, in which the disc liners are formed of bilaterally oriented polystyrene.

4. The combination of claim 1, in which the discs are coated with a film of silicone.

5. In combination, a cylindrical container having an opening therein bounded by a wall having an edge, a first plastic liner disc extending across said opening and having a peripheral portion thereof engaging said edge of the container, an annular surface on said disc disposed inwardly of said edge portion thereof and engaging said wall within said edge and extending downwardly within the opening and inclined away from the wall to form a

recess, a second plastic liner disc having a thin metal coating thereon to form a mirror surface, said second disc having an annular shoulder thereon contoured to fit said recess, said second disc removably resting snugly on top of said first plastic disc with said shoulder fitted in said recess, a cover for said opening of greater diameter than the opening and extending across said edge, said second disc being permanently secured within said cover and means to secure the cover to the container.

10 6. The combination of claim 5, wherein said inclined surface is formed by the outer surface of a depending circular bead formed in the first disc.

15 7. The combination of claim 5, wherein said inclined surface is formed by the outer surface of a depending circular bead formed in the first disc and the disc liners are both formed of bilaterally oriented polystyrene.

8. The combination of claim 7, in which the discs are coated with a film of a silicone.
